UNITED STATES PATENT OFFICE.

OLIVER L. CLARK, OF McDONALD, PENNSYLVANIA.

PUMP.

SPECIFICATION forming part of Letters Patent No. 739,831, dated September 29, 1903.

Application filed November 1, 1902. Serial No. 129,766. (No model.)

To all whom it may concern:

Be it known that I, OLIVER L. CLARK, a resident of McDonald, in the county of Washington and State of Pennsylvania, have invented 5 a new and useful Improvement in Pumps; and I do hereby declare the following to be a full, clear, and exact description thereof.

My invention relates to pumps for pumping deep wells, such as Artesian or oil wells.

Heretofore in the pumping of deep wells it has been the practice to connect the walking-beam at the top of the well to the pump at the bottom of the well by means of jointed rods, commonly known as "sucker-rods." 15 The pump was lowered into the well by means of these sucker-rods, the connection of each succeeding rod being made with the preceding one until the pump had been located at the bottom of the well. As these sucker-rods were about thirty feet in length and the pump was often located at a depth of two thousand feet or more, the labor and expense of connecting up such a long line of rods were 20 very great. Besides the first cost of procuring such a quantity of sucker-rods and making the connections there was in addition a great expense incurred in the necessary repairs. The rods break or become disconnected, and the further pumping of the well is 25 prevented until the necessary repairs have been made, causing a loss in the production of the well as well as the employment of additional men to assist in the work of repair. Furthermore, if it was desired to remove the 30 pump for the purpose of putting in new cups or for other repairs the rods were withdrawn and each disconnected as it reached the top of the well, and as the standing valve was seated in the bottom of the working barrel 35 said valve could not be removed without pulling the tubing out of the well, such an operation requiring the united efforts of three men for at least a day, with the liability of the dropping of the rods and the parting of 40 the tubing.

The object of my present invention is to provide a pump by which I dispense with the sucker-rods and substitute therefor a wire or other flexible line, which may be reeled up 45 in a very short time, while at the same time the working parts of the pump, including the standing valve, may be withdrawn by said

line or cable without removing the tubing, and the cost of operation is greatly reduced.

To these ends my invention comprises, generally stated, a working barrel, a communicating tube within which said working barrel is located, an inlet-valve on said working barrel controlling the flow of fluid to space between said tube and working barrel, a 55 check-valve controlling the outlet of said working barrel, and a pumping-piston in said working barrel whereby the oil enters the space between said working barrel and tube and passes into said working barrel, and 60 as the pumping-piston is raised the inlet-valve is closed and the fluid lifts the check-valve in said working barrel and passes to the top of the well. The raising of the pumping-piston creates a vacuum in the lower end of 65 said working barrel, and upon the down-stroke said pumping-piston will descend, its descent being further accelerated by the weight of the fluid entering the working barrel from the outer tube as the inlet-valve 70 opens and admits fluid thereto, while the check-valve of the inner tube is closed and held closed by the column of fluid above same.

To enable others skilled in the art to make 75 and use my invention, I will describe the same more fully, referring to the accompanying drawings, in which—

Figure 1 is a vertical section of a well, showing my improved pump located therein. 80 Fig. 2 is an enlarged vertical section showing the position of the parts on the upstroke. Fig. 3 is a like view showing position of parts on downstroke. Fig. 4 is a section on line 85 4-4, Fig. 3; and Fig. 5 is a section on line 5-5, 90 Fig. 3.

Like numerals indicate like parts in each of the figures.

In the drawings the numeral 2 designates an oil or like well, at the bottom of which is 95 located the tube or casing 3, having the perforated anchor or plug 3^a at the bottom thereof, through which the oil passes from the well into said tube. The tubing 4 is connected to the tube 3 in the ordinary manner. Within 100 the tube 3 is the working barrel 5, having secured thereto the standing valve 6, consisting of the cage 7 and ball 8, held therein and adapted to rest in a valve-seat 9, as in the

usual construction of such valves. The standing valve 6 has the threaded neck portion 6', adapted to engage the threaded end of the working barrel 5, and thus act to close the 5 lower end of said barrel.

At the lower end of the working barrel 5 are the packing-cups 10, which engage the inner walls of the tube 3 and pack the lower end of said tube, so that fluid entering the 10 perforated anchor passes up through valve 6 into space 11 between said tube and working barrel. The upper end of said working barrel has a shoulder 12, adapted to engage a corresponding shoulder 13 in the tube 3 when 15 said working barrel is in position. Above the shoulder 13 is the cage 14, containing the check-valve 15, which rests normally on the valve-seat 16. The check-valve 15 has the stem 17 and the angular tailpiece 18, which 20 permits the fluid to pass up around the valve when said valve is raised, as will more fully hereinafter appear. The faces of the tailpiece 18 may be grooved to facilitate the escape of the fluid when the valve is raised. 25 Any suitable form of check-valve may, however, be employed, and within the term "check-valve" I wish to include any form of valve which will act automatically to open and close the outlet of said working barrel at 30 the proper time. The working barrel 5 is also provided with orifices 19, which permit the oil in the tube 3 to enter said working barrel. Within the working barrel 5 is the pumping-piston 20, which consists of the cups 35 21, held between nuts 22 and 23. Above the cups is the valve 24, comprising the cage 25 and ball 26, adapted to rest on the valve-seat. The purpose of valve 24 is to take up any oil which may leak past the cups into the working barrel below the piston. A piston-rod 40 24 extends up through the working barrel 5 and through the stem 17 of the check-valve 15. To the upper end of the piston-rod 24 is connected the wire or other flexible cable 27, 45 said cable extending up through the tubing and attached to the walking-beam or other reciprocating device at the top of the well. It is apparent that other forms of valves 50 may be substituted for those illustrated without departing from the spirit of my invention.

The operation of my improved pump is as follows: The cable, which may be reeled up on a bull-wheel or other device at the top of 55 the well, is attached to the piston-rod 24, and the working barrel 9 is then lowered into the well through the tubing until the tube 3 is reached. The working barrel 5 then enters said tube and is forced down into same until 60 the shoulder 12 rests on the shoulder 13 of said working barrel. The pressure of oil in the well will act to raise the ball 8 of the standing valve 6, and said oil will enter the filling-space 11 between said working barrel 65 5 and said tube 3 and also pass through the orifices 19 into the working barrel 5 until same is filled. In the meantime the check-valve

15 is held to its seat by the weight of the column of fluid in the tubing. As the pumping-piston 20 is raised by the wire line the oil in 70 working barrel 5 is raised and the check-valve 15 lifts, permitting the oil to pass up into the tubing. On the raising of the pumping-piston the standing valve 6 is closed, so that the oil in the working barrel is not permitted to pass back into the tube 3 through 75 openings 19. The pressure caused by the up-stroke of the piston bears on the valve 6 and acts to hold the working barrel securely in position within the tube 3 against the tendency 80 of the piston to raise said working barrel by the friction of its cups. The oil raised by the pumping-piston passes out at the top of the well, and the piston then descends. On the descent of said piston the check-valve drops 85 to its seat and is held there by the column of oil above, while the standing valve 6 opens and more oil is admitted, which passes from the space 11 into the working barrel 5 through the openings 19. The pressure of the entering oil carries down the piston 20, assisted by 90 the vacuum in the working barrel created below said piston on its upward stroke. The piston is thus lowered by a steady positive movement without the employment of a rigid 95 connection between it and the source of power at the top of the well, such as sucker-rods or like devices. The pressure of fluid or even the vacuum alone insures the descent of the piston without its sticking or catching in the 100 tube. By my invention the pump and valves, including the standing valve, can be removed from the well without removing the tubing and repairs made with little labor and expense. Since a flexible line may be used, the 105 necessity of disconnecting each section of a line of sucker-rods is avoided, and the line may be quickly reeled up on a bull-wheel or other drum, and all the work can be done by one man. The friction of the rods within the 110 tubing is done away with and also the friction in the working barrel, so that the wear on the cups is greatly reduced.

What I claim as my invention, and desire to secure by Letters Patent, is—

115

1. In a pump, the combination of an outer tube, a working barrel within said tube and communicating therewith, a valve on said working barrel adapted to admit fluid to space between said tube and working barrel, a check-valve controlling the outlet of said working barrel, and a pumping-piston in said working barrel.

2. In a pump, the combination of an outer tube, a working barrel closed at its lower end 125 within said tube and communicating therewith, a valve on said working barrel adapted to admit fluid to space between said tube and working barrel, a check-valve controlling the outlet of said working barrel, and a pumping-piston in said working barrel.

3. In a pump, the combination of an outer tube, a working barrel within said tube and communicating therewith, a standing valve

130

secured to the lower end of said working barrel and closing the end of same, said valve being adapted to admit fluid to space between said tube and working barrel, a check-valve controlling the outlet of said working barrel, and a pumping-piston in said working barrel.

5. In a pump, the combination of an outer tube, a working barrel within said tube and having openings at the upper end thereof forming communication between said tube and working barrel, a valve on the lower end of said working barrel adapted to admit fluid to space between said tube and working barrel, a check-valve controlling the outlet of said working barrel, and a pumping-piston in said working barrel.

6. In a pump, the combination of an outer tube, a working barrel within said tube and communicating therewith, packing material on the lower end of said working barrel engaging the walls of said tube, a valve on said

working barrel adapted to admit fluid to space between said working barrel and said tube, a check-valve controlling the outlet of said 25 working barrel, and a pumping-piston in said working barrel.

6. In a pump, the combination of an outer tube, a working barrel within said tube, said working barrel being closed at its lower end 30 and having an opening forming communication between said working barrel and said outer tube, a valve carried by said working barrel adapted to admit fluid to the space between said tube and working barrel, a check-valve controlling the outlet of said working barrel, a pumping-piston in said working barrel and a valve on said pumping-piston.

In testimony whereof I, the said OLIVER L. CLARK, have hereunto set my hand.

OLIVER L. CLARK.
